(57) **CLAIM**

The ornamental design for deployable flight recorder housing, as shown and described.

DESCRIPTION

FIG. 1 is a perspective view from the bottom of a deployable flight recorder housing showing our new design;

FIG. 2 is a perspective view from the top of the deployable flight recorder housing;

FIG. 3 is a back side view of the deployable flight recorder housing;

FIG. 4 is a bottom view of the deployable flight recorder housing;

FIG. 5 is a front side view of the deployable flight recorder housing;

FIG. 6 is a top view of the deployable flight recorder housing;

FIG. 7 is a right side view of the deployable flight recorder housing, the left side view being a mirror image thereof; and, FIG. 8 is a perspective view of the deployable flight recorder housing, shown in an opened position.

In the drawings, shaded areas represent environment that forms no part of the claim.
